BOILER

George J. Graves and Edward J. Graves,
Jamestown, N. Y.

Application January 11, 1933, Serial No. 651,194

9 Claims. (Cl. 122—19)

Our invention relates to improvements in boilers and particularly to gas fired automatic vapor, steam, or hot water boilers for house heating.

5 A primary object of our invention is to provide a boiler of the down draft type with increased capacity and economy without a corresponding increase in boiler size.

Another object is to provide a boiler the burner 10 of which is contained in an inner removable casing.

A further object is to provide a combustion chamber having two bottom plates and a series of annular flanges welded to its top.

15 A still further object is to provide an inner smoke box cover shell having horizontal projections equi-spaced on its outer periphery.

Other new and useful objects will be apparent 20 from the following description and the accompanying drawings in which like numerals are employed to designate like parts throughout.

Figure 1 is a vertical section of a boiler embodying my invention;

Figure 2 is a front elevation thereof;

25 Figure 3 is a section on the line 3—3 of Figure 1;

Figure 4 is a section on the line 4—4 of Figure 1;

30 Figure 5 is a section on the line 5—5 of Figure 1;

Figure 6 is a plan view of the combustion chamber top;

Figure 7 is a section on the line 7—7 of Figure 1;

35 Figure 8 is a side view of the inner smoke box shell;

Figure 9 is a plan view of the under side of the inner shell, and,

Figure 10 is an enlarged vertical section 40 through the boiler wall at the point where the casings and combustion chamber meet.

The numerals 11 denote the supporting legs, and 45 12 the side wall of a combustion chamber mounted thereon. The combustion chamber has a bottom plate 13 pierced in its depressed center with a hose coupling 14 to carry off possible leakage or condensation and also an inner bottom plate 15 with a large opening 16 formed in the same. A door 17 mounted in the lower 50 front of the combustion chamber wall opens into the space formed between the plates 13 and 15. This door 17 is always closed to prevent cold air from passing up through the combustion chamber and boiler except when secondary air is 55 desired, in which case it is opened automatically

by apparatus not shown. Mounted directly above the door 17 in grooves 18 formed in the ends of the combustion chamber wall 12 is a vertically sliding door 19, said door having an opening in its face closed by a hinged door 20, 5 and a semi-circular opening 21 cutout midway of its bottom edge. This construction is best shown in Figures 2 and 5. The combustion chamber cover 22 (best shown in Figure 6) is shaped to fit the contour of the side wall 12, 10 and has a circular opening 23, and upstanding annular flanges 24, 25, and 26, spaced around the said opening.

The numeral 27 indicates the circular casing, 15 having upper and lower flue sheets 28 and 29 which hold in place vertical heat conducting tubes 30. The casing 27 is pierced for one or more inlet pipes 31, and outlet pipe or pipes 32, and carries a gauge 33. The boiler casing is composed of an inner shell 34, insulating 20 material 35, and outer shell 36 which is best shown in Figure 1, these shells being pierced for the various water pipes and gauges. This arrangement forms a circular down draft chamber 36^a between the boiler casing 27 and the 25 inner boiler shell 34. The smoke pipe connection 37 is welded to the lower back of the shell 34 and comes out through an opening in the outer shell 36. The shell 36 is lapped in the back so that it can be fitted over the smoke 30 pipe connection 37.

An inwardly dished smoke box shell 38 having its outer edge bent downwards forming an annular flange 39 and having equi-spaced U-shaped brackets or projections 40 extending horizontally from the flange 39, is placed on the inner shell 34, the projections 40 touching the outer shell 36. This makes for equal spacing between the two shells as the act of packing insulating material 35 between them would ordinarily cause the outside shell to move towards the inside shell at points where the insulating materials are packed the lightest. An outer smoke box shell 41 goes over the outer boiler shell 36 and the space between it and the inner 45 shell 38 is packed with insulating material 35.

The burner used consists of a feed pipe 42, cross pipe 43, and pieces of cast iron pipe 44 electrically welded at right angles to nipples 44^a on the top of the cross pipe 43, the pipes 44 having 50 a double row of burner tip holes 45 spaced about one-half inch apart and drilled on an angle of about 30° from the horizontal length of each of said pipes. The use of the nipples 44^a raises the burner tubes a short distance above 55

the cross pipe 43 and prevents flarebacks when the burner goes out. Short legs 43^a are welded to the extreme ends of the cross pipe 43 to support the burner on the plate 15.

5 The burner is assembled in a steel or refractory cylindrical casing 46 of a height equal to the distance between the inner bottom plate 15 and the combustion chamber cover 22, and of a diameter slightly larger than the circular opening 23 in the combustion chamber cover. This forms a dead air space 46^a between the burner casing and the outside wall 12 which tends to keep the outer wall cool and prevents its paint from peeling off. This air space is best shown in Figure 1. A small hinged door 47 is placed 10 in the upper front of the casing 46 through which the pilot or burner can be lighted or examined. Stops 48 welded to the upper surface of the plate 15 centralize the casing 46 in its proper position in the combustion chamber. An 15 advantage of the inner burner casing 46 is that it forces the secondary air which enters through door 17 and hole 16, to rise directly through and past the burner pipes thus insuring thorough combustion. This is best illustrated in Figure 1.

20 To assemble the parts of the device the casing 46 which has the burner assembly mounted therein is inserted into the lower or combustion compartment until it strikes the stops 48, the 25 burner being held level by the short legs 43^a. The door 19 is then slid into place. The boiler assembly is then mounted inside of the guide ring or flange 24 and the shells 34 and 36 are placed around the flanges 25 and 26. The outer shell 36 is lapped in the back, so that it may 30 fit over the smoke pipe 37, and is held together by suitable screws or the like.

35 The various pipe nipples may then be screwed into place. The inner smoke box shell 38 is then fitted to the top of the inner shell 34 after which insulating material 35 is packed between the 40 wall shells 34 and 36. More insulating material 35 is packed on top the inner smoke box shell 38 after which the outer shell 41 is welded in 45 place on top of the wall casing 36. It may be noted that all joints and connections are welded except the lap seam at the back of the outer shell 36, also that the assembly of the burner and the circular shell 46 are removable from the combustion chamber.

50 Having thus described our invention, what we wish to claim by Letters Patent is:

1. In a boiler, a combustion chamber having an outer wall and two spaced bottom plates, the 55 upper plate having an opening in approximately its center, a door in the combustion chamber wall opening into the space between the said bottom plates, an inner combustion chamber comprising a casing removably mounted on the 60 upper combustion chamber plate and enclosing the opening in the same, a burner mounted in and removable with the inner casing, and a heating chamber mounted on the combustion chamber.

65 2. In a boiler, a combustion chamber having an outer wall and two spaced bottom plates, the upper of said plates having a circular opening in its center portion, stops projecting from the upper surface of the upper plate around the 70 sides and back of the circular opening, a door in the combustion chamber wall opening into the space between the two bottom plates, a circular shell removably placed on the upper combustion chamber plate and properly positioned by the stops, a burner fixed in the circular

75 shell and removable with the same, and a heating chamber mounted on the combustion chamber.

3. In a boiler, a combustion chamber, a heating chamber mounted thereon, said heating chamber having walls comprising inner and outer shells with insulating material between same, a smoke box cover comprising inner and outer shells each of the shells having its edges bent into a downwardly extending flange seated on 10 the tops on the inner and outer shells respectively, spaced projections extending horizontally and outwardly from the flange of the inner smoke box cover shell, said projections being of such outward extent that the boiler shells will 15 be held in their proper spaced relation.

4. In a boiler, a combustion chamber, a cover for said chamber having a large central opening, continuous vertical flanges spaced one within the other formed on the combustion chamber 20 cover around the opening in the same, a boiler wall comprising inner and outer shells and a casing mounted on the combustion chamber cover, said shells and casing each fitting against one of the vertical flanges on the said cover, and a smoke box cover comprising inner and outer shells each of the shells having its edges bent into a downwardly extending flange seated on 25 the tops of the inner and outer boiler wall shells respectively, spaced projections extending horizontally and outwardly from the flange of the inner smoke box cover shell, said projections being of such outward extent that the boiler wall shells will be held in their proper spaced relation.

30 5. In a boiler, a combustion chamber, a cover for said chamber having a circular opening, annular upstanding flanges spaced one within the other fixed on the combustion chamber top around the opening in the same, and a boiler 35 wall comprising inner and outer wall shells, and a casing mounted on the combustion chamber each wall shell and the casing abutting one of the upstanding annular flanges, a smoke box cover comprising inner and outer shells, each of 40 the shells having its edges bent into a downwardly extending flange seated against and alongside the tops of the inner and outer boiler wall shells, respectively, spaced projections extending laterally from one smoke box cover 45 flange toward the other and said projections being of such a length that the boiler wall shells will be held in their proper spaced relation.

50 6. In a boiler, a combustion chamber, a heating chamber mounted thereon, said heating chamber having an outer wall comprising inner and outer shells with insulating material between same, a smoke box cover comprising inner and outer shells, each of the shells having 55 its edges bent into a downwardly extending flange seated against and alongside the tops of the inner and outer heating chamber shells, respectively, spaced projections extending laterally from one smoke box cover flange toward the 60 other and said projections being of such a length that the heating chamber shells will be held in their proper spaced relation.

65 7. In a boiler, a combustion chamber, an inner combustion chamber comprising a casing 70 removably mounted therein, a burner mounted in the inner casing and removable with the same, a heating chamber mounted on the first named combustion chamber, said heating chamber having spaced walls, and a part closure for 75

the upper end of said heating chamber comprising spacedly interfitting caps having depending flanges and means for uniformly spacing said flanges and carried by one of the same.

- 5 8. In a boiler, a combustion chamber having an outer wall and two spaced bottom plates, the upper plate having an opening in approximately its center, a door in the combustion chamber wall opening into the space between the said bottom plates, and an inner combustion chamber comprising a casing removably mounted on the upper combustion chamber plate and enclosing the opening in the same.
- 10

9. In a boiler, a combustion chamber having an outer wall and two spaced bottom plates, the upper plate having an opening in approximately its center, a door in the combustion chamber wall opening into the space between the said bottom plates, an inner combustion chamber comprising a casing removably mounted on the upper combustion chamber plate and enclosing the opening in the same, and a burner mounted in and removable with the inner casing. 5 10
